CLAIM

The ornamental design for a three button remote control with flashlight, as shown and described.

DESCRIPTION

FIG. 1 is a perspective view of a three button remote control with flashlight showing my new design.

FIG. 2 is a right side elevational view of the invention.

FIG. 3 is a left side elevational view of the invention.

FIG. 4 is a front elevational view of the invention.

FIG. 5 is a rear elevational view of the invention.

FIG. 6 is a top plan view of the invention; and,

FIG. 7 is a bottom plan view of the invention.
